Specification for Design.

Patented July 6, 1920.

Application filed October 28, 1919. Serial No. 334,094. Term of patent 14 years.

To all whom it may concern:

Be it known that I, CHARLES E. MASON, a citizen of the United States, residing at Detroit, in the county of Wayne and State of Michigan, have invented a new, original, and ornamental Design for Manifold-Brackets, of which the following is a specification, reference being had to the accompanying drawing, forming part thereof.

Figure 1 is a side elevation of a manifold bracket showing my new design; Fig. 2 is a front elevation of the construction illustrated in Fig. 1, and Fig. 3 is a plan of the construction illustrated in Fig. 1.

I claim:

The ornamental design for a manifold bracket, as shown.

CHARLES E. MASON.
